UNITED STATES PATENT OFFICE.

MERRIL PINKSTON, OF GARNETT, KANSAS.

TRESTLE FOR SCAFFOLDING.

SPECIFICATION forming part of Letters Patent No. 340,004, dated April 13, 1886.

Application filed January 30, 1886. Serial No. 190,290. (No model.)

To all whom it may concern:

Be it known that I, MERRIL PINKSTON, a citizen of the United States, residing at Garnett, in the county of Anderson and State of Kansas, have invented certain new and useful Improvements in Trestles for Scaffolding; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

This invention relates to trestles for scaffolding, and has for its object to provide a simple, inexpensive, and durable trestle, which is capable of being folded for transportation and storage, and can be adjusted to different heights, as desired; and it consists of the parts and combinations of parts hereinafter described and claimed.

In the accompanying drawings, forming a part of this specification, Figure 1 is an end view of my improved trestle; Fig. 2, a side view; Fig. 3, a perspective view, and Fig. 4 a detail view.

Similar letters refer to similar parts throughout the several views.

- A represents the main supporting-legs, and B the props therefor. These latter are pivoted to the main legs A, so that the latter can be folded within them when it is necessary to move the trestle from place to place or to store it away. By moving these props toward or from the main legs the height of the scaffolding is regulated. A chain or rope, C, is secured to one of the lower cross-bars, D, of the main legs A, and extends across to the lower cross-bar, E, of the props B, and is there secured by a hook in its end to a staple in said bar E, or in any other suitable manner. The main legs A are suitably braced by means of the bars D on one side and the bars F on the other. These bars are grooved on their adjacent surfaces, as at a, Fig. 4, for the reception of the adjustable upright G, for which the said bars form a brace, permitting at the same time its sliding up and down therein, and thus providing for the raising or lowering of the scaffolding to suit rooms of different heights, as this invention is more expressly designed for the use of indoor workmen; but it may be used

outside, if desired. The adjustable upright G is provided with a number of perforations or openings, b, at suitable distances apart, which correspond in size to an opening or perforation, c, in the short upper brace-bar, H, of the main legs A. A pin, d, fastened to the end of a chain or cord, e, which is secured to one of the main legs, is intended to be inserted through the opening c into one of the openings b in the upright, to secure the same against movement after it has been adjusted to the proper or desired height. At the upper end of the upright G a groove h, is formed, either by means of the two cheek pieces h', secured to the side of the sides of the upright, or the end of the upright may be of one piece of greater diameter than its body and the groove cut therein. In either event the bottom surface of the groove is rounded, so that a log placed therein will be supported level and prevented turning by means of the cheek-pieces h'. Through the cheek-pieces or enlarged end of the upright the latter may be supported without using the pin d, when the upright is in the position shown in Fig. 3, as in that case the cheek-pieces will rest on the upper ends of the legs A. It will thus be seen that I provide a very simple device, whereby the same trestle may be used in rooms of different heights by simply adjusting the props nearer to or farther apart, and that a still greater height may be reached by merely sliding the upright G in its grooves or ways and securing it thereby means of the pin d.

I am aware that adjustable perforated uprights, forming a support for a cross-bar on which the scaffolding rests, have been used in folding trestles, and I do not desire to be understood as claiming such, broadly.

Having thus described my invention, what I claim as new, and desire to secure by Letters Patent, is—

1. The herein-described trestle for scaffolding, comprising the main legs A, the pivoted props B, the grooved brace bars D F, the chain C, the perforated bar H, and the adjustable upright G, provided with the perforations b, grooved upper end, h, and pin d, substantially as and for the purpose described.

2. The combination, in a trestle having adjustable props, of the adjustable upright G, having the perforations b, the grooved cross-

bars D F, the perforated cross-bar H, and the pin d, substantially as and for the purpose described.

3. The combination, in a trestle, of the adjustable upright G, having the grooved upper end, h, and the grooved cross-bars, substantially as and for the purpose described.

In testimony whereof I affix my signature in presence of two witnesses.

MERRIL PINKSTON.
